UNITED STATES PATENT OFFICE.

THURE DAHL, OF NEW YORK, N. Y., ASSIGNOR TO LIGHTOLIER COMPANY, A CORPORATION OF NEW YORK.

DESIGN FOR A FIXTURE-ARM FOR LIGHTING-FIXTURES.

59,415.

Specification for Design.

Patented Oct. 18, 1921.

Application filed February 10, 1921. Serial No. 444,039. Term of patent 3½ years.

To all whom it may concern:

Be it known that I, THURE DAHL, a subject of the King of Sweden, residing at New York city, in the county of New York and State of New York, have invented a new, original, and ornamental Design for Fixture-Arms for Lighting-Fixtures, of which the following is a specification, reference be-

ing had to the accompanying drawing, forming part thereof.

The figure is a side view of a fixture arm for lighting fixtures showing my new design.

I claim:

The ornamental design for a fixture arm for lighting fixtures as shown.

THURE DAHL.
